CONTAINER

Cecil R. Brown, Verona, N. J., assignor to Burroughs Wellcome & Co. (U. S. A.) Inc., New York, N. Y., a corporation of New York

Application October 24, 1936, Serial No. 107,338

2 Claims. (Cl. 312—112)

This invention relates to containers and more particularly to a container for a series of articles such as a first-aid kit which may be closed for carrying and is provided with a hinged front or cover adapted to open to form a tray when the container is hung on a wall.

An object of the invention is to provide a cheap, simple, convenient and attractive container of the type above indicated.

Various other objects and advantages will be apparent as the nature of the invention is more fully disclosed.

Although the novel features which are believed to be characteristic of this invention will be particularly pointed out in the claims appended hereto, the invention itself will be better understood by referring to the following description, taken in connection with the accompanying drawing in which one embodiment thereof has been set forth for purposes of illustration.

In the drawing:

Fig. 1 is a perspective view of the container showing the front open to form a tray;

Fig. 2 is a section taken along the line 2—2 of

Fig. 1;

Fig. 3 is a partial transverse section showing the front in closed position; and

Fig. 4 is a bottom plan view of the container illustrating the hinge construction.

Referring to the drawing more in detail, the container is shown as comprising a body section 10 having a back 11, sides 12 and ends 13 secured together to form an open front container. The body section is shown as formed from a blank 35 which is cut and folded to form tabs 15 at the ends of the sides 12, said tabs being folded over and secured to the ends 13 in any convenient manner.

A closure or cover 16 is formed with a top 17 and with upstanding flanges 18 which are adapted to seat over the sides and ends of the body portion 10. The cover 16 is secured to the body section 10 by means of a hinge comprising hinge plates 19 and 20 which are secured respectively to the lower side 12 of the body section and to the inner face of the flange 18 of the cover. The plates 19 and 20 are joined by a hinge knuckle 21 which extends outwardly from the lower side of the body section. The flange 18 to which the hinge plate 20 is secured is provided with a curved tab 22 which extends over a portion of the hinge knuckle 21 and engages the hinge plate 19 to form a stop for holding the closure in horizontal position as illustrated in Figs. 1 and 2 so that the cover can be utilized as a tray.

A pair of ears 25 are pivoted to the back 11 as by rivets 26. These ears are provided with slots 27 which are adapted to receive a nail or the like for hanging the container on a wall. The body

portion 10 and closure 16 are provided with suitable catch members 30 and 31 to hold the container closed. A handle 32 is attached to the top side 12 of the body portion to permit the container to be readily carried when desired.

By means of the construction above described, the container is adapted to be readily closed and carried or to be hung on a wall in such a manner that the contents thereof are readily accessible. The closure 16 is held in horizontal position when open to form a tray so that the contents of the container can be more readily handled. This feature is of importance in a first-aid kit which may be hung upon the walls of a factory where space is limited and where a clean table or the like may not be available for supporting the first aid materials as they are being assembled for use.

The present invention may be put to various uses as will be apparent from a consideration of the embodiment disclosed. It is to be understood that various changes and modifications may be made therein without departing from the scope of the invention which is to be limited only in accordance with the following claims when interpreted in view of the prior art.

What is claimed is:

1. A container comprising a body section having sides, ends and back and open at the front, means to engage a wall support for hanging the container thereon, a front closure hinged to the lower side of said body section to open downwardly, said closure having side flanges adapted to seat over said sides and ends and a hinge for said closure comprising hinge plates extending substantially the full width of said container and secured to the lower side of said body member and to the inside of the corresponding flange of said closure respectively, said hinge having a knuckle extending downwardly from said hinge members in the closed position of said closure, said last mentioned flange being extended over the entire length of said hinge knuckle to form a stop for holding the closure extended horizontally and to conceal said hinge knuckle when the front closure is in closed position.

2. A container comprising an open top body section, a cover therefor having flanges adapted to seat outside of the walls of said body section and a hinge for said cover comprising hinge plates extending along substantially the full width of said container and secured to an outer wall of said body section and to the inner surface of the corresponding flange of said cover, respectively, said last mentioned flange being extended over the entire length of the hinge knuckle to form a stop for limiting the movement of said closure and to conceal the hinge knuckle when said cover is in closed position.
